UNITED STATES PATENT OFFICE.

HENRY JACOBS, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed January 17, 1920. Serial No. 352,172.

To all whom it may concern:

Be it known that I, HENRY JACOBS, a citizen of the United States, residing in borough of the Bronx, in the county of the Bronx, city and State of New York, have invented certain new and useful Improvements in Typewriting Machines, of which the following is a specification.

This invention relates to back-spacing mechanism for typewriting machines.

The main object of this invention is to provide back-spacing mechanism, simple in design, having few parts, and adapted to relieve the carriage escapement rack of the wear incident to the use of back-spacing mechanism.

In carrying out this invention, provision is made of a back-space rack, in addition to the usual escapement rack mounted on the carriage for movement into and out of mesh with a pinion connected with the escapement wheel.

The mechanism by means of which the back-space lever actuates the back-space rack may be mounted on a single bracket attached to the frame, so that substantially no changes in the frame of the machine are necessary to enable this part of the present invention to be applied thereto.

The mechanism by which the back-space lever actuates the back-space rack is so constructed and arranged as to avoid any substantial loss of power, thus rendering the back-space lever easy to operate.

In back-spacing the carriage, the escapement rack, due to the manner in which it is mounted on the carriage, tends to ride over the teeth of the pinion with which it usually co-operates, thus tending to prevent proper positioning of the carriage in the back-spacing operation. In order to prevent such defective operation, provision may be made of a resilient arm mounted on the back-space lever and having a suitably shaped end, which, upon actuation of the back-space lever, is moved into engagement with the rack to prevent movement of the rack away from the pinion.

The resilient arm, just referred to may also be utilized in limiting the movement of the carriage by the back-space mechanism. To this end, a portion of the resilient arm is so shaped that, upon depression of the back-space lever, it will be inserted between two adjacent teeth of the escapement

rack, movement of the carriage in the back-spacing operation carrying the resilient arm therewith until it is brought into engagement with a fixed stop, thus limiting the movement of the carriage. The form given to the upper end of the resilient arm to adapt it for both purposes specified, is that of a hook which, upon actuation of the back-space lever, embraces the escapement rack.

Other features and advantages will hereinafter appear.

In the accompanying drawings, Figure 1 is a diagrammatic side elevation, partly in section, showing the invention applied to an Underwood standard typewriter.

Figure 2 is a fragmentary front elevation of a portion of the machine with my invention applied thereto, the parts being shown in their normal positions.

Figure 3 is a view, similar to Figure 2, but showing the parts in their actuated positions.

Figure 4 is a perspective view, showing parts in detail.

A cylindrical platen 1 is supported by an axle 2, journaled in the platen frame 3 on the carriage 4, said carriage 4 being movable transversely of the machine on a front rail 5 and a rear rail 6.

Said carriage 4 is urged to the left by means of the usual band or strap 7 and spring-drum 8, and its movement is controlled by means of escapement mechanism comprising a rack 9, carried by arms 10 pivoted at 11 on the carriage, and a pinion 12 with which said rack is normally in mesh. Said pinion 12 has the usual one-way connection with an escapement wheel 13 by means of pawls 14 pressed by springs 15 into engagement with said pinion 12. Said escapement mechanism is controlled in a well-known manner by means of a fast dog 16 and a loose dog 17, carried on a dog-rocker 18 mounted on pivots 19.

In order to back-space the carriage, a back-space rack 20 is attached to the carriage at the front thereof, and provision is made of a back-space pawl 21, carried by an arm or pawl-carrier 21^a extending substantially parallel to said rack 20. The arm or pawl-carrier 21^a is pivoted, by means of a shoulder screw 22, on the upright arm 23 of a bell-crank 24, the horizontal arm 25 of which is connected by means of a shoul-

dered screw 26 to a link 27, actuated by means to be described hereinafter.

Said bell-crank 24 is pivotally mounted, by means of a shouldered screw 29, on a bracket 30 preferably formed of a single piece of sheet-metal, suitably cut and bent into shape as best shown in Figure 4. In securing the bracket 30 to the frame, use is made of a screw 31, which secures one of the ribbon-spool brackets 32 to the side of the frame; and said bracket is also secured to the frame by a screw 33, passing through lug 34 at the forward end of said bracket.

In order to limit the movement of bell-crank 24, its upper and lower arms 23 and 25, respectively, are supplied with projections 35 and 36, which, upon movement of the bell-crank to its limiting positions, engage portions 37 and 38, respectively, of said bracket. The pawl 21 is urged toward the rack 20 by means of spring 39, connected to the left-hand end of the arm 21^a and to a pin 40 on the bracket.

Link 27 is connected at its lower end, by means of a shouldered screw 41, with a back-space lever 42, on the forward end of which is a back-space key 43, said back-space lever 42 being pivotally supported, by means of a shouldered screw 44, on a bracket 30 connected by a screw 46 to a cross-bar 47 of the machine. A spring 48 connected at one end to a pin 49 on link 27, and at the other end to a hook 50 on bracket 30, normally maintains back-space lever 42 and bell-crank 24 in the position shown in Figure 2.

The portion of bracket 30 on which said bell-crank 24 is pivoted is extended to the right along arm 21^a, and at its end is provided with a finger 51, projecting from its lower edge and bent upwardly to form a guiding device for the right-hand end of said arm 21^a. In order to control the movement of pawl 21 into and out of engagement with said rack 20, provision is made of a pin 52, positioned on the bracket near finger 51 and projecting into an opening 53 in said arm 21^a. It will be seen that, upon movement of the pawl-carrier to the left, pin 52 will be engaged by a cam 54 at one side of the opening 53, and the pawl 21 will be withdrawn from said rack 20.

In order to prevent the escapement rack 9 from riding over the pinion 12 when back-spacing is effected, provision is made of a resilient arm 55, preferably integral with back-space lever 42, extending upwardly and rearwardly to a position slightly to the rear of the escapement rack 9 at the left of the escapement wheel. The upper end of said resilient arm 55 is in the form of a hook, having a portion 56 to engage over said rack upon depression of the back-space lever and a shoulder 57 to pass between two adjacent teeth of said rack. As a result of

the resiliency of the arm 55, the upper end thereof may be carried along by said rack 9 during the back-spacing operation, and this fact is made use of in providing means for limiting the back-spacing movement. In order to utilize the resilient arm 55 for the last-mentioned purpose, provision is made of a stop 58, preferably on the bracket carrying the escapement wheel, so positioned as to be engaged by the upper part of said resilient arm 55 at the end of the back-spacing movement.

In the usual operation of the machine, depression of a character key 59 will act, through suitable means, to swing a type-bar 60 against the front of the platen, and, at the end of the forward swing of the type-bar, the dog-rocker 18 will be rocked in the usual manner to move loose dog 17 out of engagement with the escapement wheel and to move fixed dog 16 into engagement therewith. The connections between the character keys and the type-bars and the means for actuating the fixed and loose dogs may be substantially the same as the corresponding mechanism in the patent to Arthur A. Johnson, No. 1,215,307, dated February 6, 1917.

In order to prevent backward movement of the escapement wheel when the carriage is returned to the right in the ordinary operation of the machine, provision is made of a back-check pawl 61, pivoted at 62 on the dog-rocker 18 and urged to its limiting left-hand position by means of a spring 63. In the present mechanism, the back-check pawl 61 is utilized to prevent backward turning of the escapement wheel during the back-spacing operation. It will be evident that the escapement wheel, in moving from the position shown in Figure 2 to that in Figure 3, in which the back-check pawl 61 becomes effective, passes through a space corresponding to slightly less than a letter-space movement of the carriage; and, in order to insure an effective back-spacing of one letter-space, it will be necessary to back-space the carriage slightly less than two letter-spaces, due to the lost motion of the escapement wheel shown in Figures 2 and 3.

When back-spacing is desired, key 43 is depressed, and, through link 27, bell-crank 24 is moved from the position shown in Figure 2 to that shown in Figure 3, and the pawl-carrying arm 21^a moved to the right. In such movement to the right of the pawl-carrying arm 21^a, cam 54 will move past pin 52 and permit arm 21^a to be moved by its spring 39, so as to bring pawl 21 into engagement with the back-space rack 20, movement of 21^a being effective thereafter to move the back-space rack 20 and consequently the carriage to the right. In such movement of the carriage to the right, the pinion 12 and escapement wheel 13 will be reversely rotated together until the tooth 130

shown at the right of the back-space pawl 61 in Figure 2 is brought into engagement with said back-space pawl 61, as seen in Figure 3. The movement of the carriage 5 and the escapement rack 9 must then be continued until the pinion 12 has been rotated relatively to the escapement wheel 13 an amount corresponding to a one-letter-space movement of the carriage. Concomitantly 10 with such actuation of the carriage by means of the back-space pawl 21, the resilient arm 55 is moved from the position shown in Figure 1 to a position in which portion 56 engages over rack 9, and shoulder 57 engages between the teeth of rack 9. The 15 resilient arm 55 in this position will act to maintain the rack 9 in mesh with pinion 12, and, due to the resiliency of said arm 55, the upper end thereof will be carried to 20 the right by said rack 9 until brought into engagement with said stop 58, thus limiting the back-space movement by means of key 43 and preventing any overrunning of the carriage. Upon release of the back-space 25 key 43, the carriage will be moved to the left by means of strap 7 and spring-drum 8 until the escapement wheel is rotated from the position shown in Figure 3 to that shown in Figure 2, but since the pinion 12 has 30 been rotated a suitable amount relatively to the escapement wheel 13, the carriage will be positioned one letter-space to the right of its former position.

As a consequence of having cam 54 on 35 the pawl-carrying arm 21 forming part of the boundary of the opening 53 in which the pin 52 extends, movement of the arm 21 with reference to the bracket is limited, and the movement of said pawl-carrying 40 arm may be controlled to some extent by means of the edge portions 64 and 65 at the sides of said opening.

Variations may be resorted to within the 45 scope of the invention, and portions of the improvements may be used without others.

Having thus described my invention, I claim:

1. In a typewriting machine, in combination, a carriage, a rack on said carriage, 50 means, including a back-space lever, to back-space said carriage, a resilient arm connected with said lever, and having a forked rear end to engage said rack, and a fixed stop, actuation of said lever causing said resilient 55 arm to be swung to bring one part of the forked portion between the teeth of said rack, and the other part on the opposite side of the rack to prevent lifting thereof, and said forked end to be carried by said rack 60 against said stop, to limit the movement of said carriage by the back-space lever.

2. In a typewriting machine, in combination, a carriage, escapement mechanism including a rack attached to said carriage, a 65 second rack attached to said carriage, a

back-space lever, means actuated by said back-space lever to back-space said carriage by means of said second rack, and means actuated by said back-space lever to co-operate with said first-mentioned rack, to limit 70 the back-space movement of said carriage.

3. In a typewriting machine, in combination, a carriage, escapement mechanism including a rack pivotally mounted on said carriage, a fixed stop, back-spacing mechanism including a back-space lever, a resilient member having a hooked end adapted to embrace said rack, and to enter between the teeth thereof on one side, and means whereby actuation of said back-spacing mechanism will cause the hooked end of said resilient member to embrace said rack, and be moved therewith in the back-spacing movement until engaged by said fixed stop. 80

4. In a typewriting machine, in combination, a carriage, escapement mechanism therefor, including an escapement wheel, a pinion having a one-way driving connection therewith, and a rack pivotally mounted on 90 said carriage for movement into and out of mesh with said pinion, a back-space rack on said carriage, means, including a back-space lever, for actuating said back-space rack, and means, rendered effective by actuation 95 of said back-space lever, to engage the escapement rack and thereby prevent withdrawal of the escapement rack from the pinion, and to limit the extent of the back-space movement of the carriage. 100

5. In a typewriting machine, in combination, a carriage, escapement mechanism therefor, including a toothed rack on said carriage, a stop beneath said rack, a member adapted to engage between the teeth of 105 said rack, back-space mechanism independent of said rack, and means actuated by said back-space mechanism for causing said member to engage between the teeth of said rack, and to be moved thereby until brought 110 into engagement with said stop.

6. In a typewriting machine, in combination, a carriage, escapement mechanism therefor, including an escapement wheel, a pinion having a one-way driving connection 115 therewith, and a rack pivotally mounted on said carriage for movement into and out of mesh with said pinion, a back-space rack on said carriage, means, including a back-space lever, for actuating said back-space rack, 120 and means, rendered effective by actuation of said back-space lever, to prevent said escapement rack from being moved out of mesh with said pinion.

7. In a typewriting machine, in combination, a carriage, escapement mechanism therefor, including an escapement wheel, a pinion having a one-way driving connection with said escapement wheel, and an escapement rack mounted on said carriage, said 125 130

pinion and rack being separable to disconnect the carriage from the escapement mechanism, back-space mechanism including a back-space lever, said back-space mechanism being independent of said rack, and means, rendered effective by actuation of said back-space lever, to prevent the separation of the escapement rack and the pinion.

8. In a typewriting machine, in combination, a carriage, escapement mechanism therefor, including an escapement wheel, a pinion having a one-way driving connection with said escapement wheel, and an escapement rack mounted on said carriage, said pinion and rack being separable to disconnect the carriage from the escapement mechanism, back-space mechanism including a back-space lever, said back-space mechanism being independent of said rack, and means, rendered effective by actuation of said back-space lever, to prevent the separation of the escapement rack and the pinion and to act through said escapement rack to limit the movement of the carriage in the back-space direction.

9. In a typewriting machine, in combination, a carriage, escapement mechanism, including a pinion on a fixed support and a rack on said carriage mounted for movement into and out of mesh with said pinion, back-spacing mechanism, and a lever pivoted on said machine, one arm of said lever being adapted to actuate said back-spacing mechanism, and the other arm of said lever being adapted to engage said rack when the back-spacing mechanism is actuated and prevent withdrawal of said rack from said pinion.

10. In a typewriting machine, in combination, a carriage, a toothed rack on said carriage, a fixed stop, and back-space mechanism, including a back-space lever and a flexible arm on said back-space lever, whereby, upon actuation of the latter, a portion of said flexible arm will be inserted between adjacent teeth of said rack and moved therewith until said flexible arm is brought into engagement with said stop.

11. In a typewriting machine, in combination, a carriage, a rack thereon, and means

to co-operate with said rack to back-space said carriage, including a pawl to engage with said rack, a substantially horizontal pawl-carrying arm, a bell-crank having an upright arm on which said pawl-carrying arm is pivoted and a substantially horizontal lower arm, a back-space lever, a link connecting the lower arm of said bell-crank with said back-space lever, a bracket on which said bell-crank is pivoted, and a spring connecting said link and said bracket, to urge said back-space lever and bell-crank to their normal positions.

12. In a typewriting machine, in combination, a carriage, a rack thereon, means to co-operate with said rack to back-space said carriage, including a pawl to engage with said rack, a substantially horizontal pawl-carrying arm, a bell-crank having an upright arm on which said pawl-carrying arm is pivoted and a substantially horizontal lower arm, a back-space lever, a link connecting the lower arm of said bell-crank with said back-space lever, a bracket on which said bell-crank is pivoted, and a spring connecting said link and said bracket, to urge said back-space lever and bell-crank to their normal positions, and a spring co-operating with said pawl-carrying arm and said bracket to urge said pawl toward said rack.

13. In a typewriting machine, in combination, a carriage, a rack therefor, and means to cooperate with said rack to back-space said carriage, including a pawl to co-operate with said rack, a substantially horizontal pawl-carrying arm, a bell-crank having an upright arm on which said pawl-carrying arm is pivoted and a substantially horizontal lower arm, a back-space lever, a link connecting the lower arm of said bell-crank to said back-space lever, a bracket on which said bell-crank is mounted, and guiding means for the right-hand end of said pawl-carrying arm supported by said bracket.

HENRY JACOBS.
